UNITED STATES PATENT OFFICE.

JOHN BALDWIN ADAMS, OF BERHAMPORE, WELLINGTON, NEW ZEALAND.

BUOYANT WEARING APPAREL FOR SWIMMING OR LIFE-SAVING PURPOSES.

Application filed October 4, 1926, Serial No. 139,523, and in Great Britain June 15, 1926.

This invention concerns improvements in or relating to buoyant wearing apparel for swimming or life-saving purposes and has for its purpose, broadly speaking, the provision of an efficient but simple and inexpensive device of the so-called "jacket" form.

The type of device to which the invention relates more particularly is that in which one or more hinged buoyant members is or are employed to ensure stability when the device is in use.

The main objects of the invention are to provide a device of this kind which will be reversible (i. e. can be put on either way correctly), will have increased buoyancy while being of simple construction, and can be tied on the wearer quickly and yet in such manner that displacement thereof is prevented. The tying means are so arranged as to prevent the possibility of choking of the wearer.

A further object is to provide a jacket that will be applicable to any wearer, of whatever size or sex.

In order that the invention may be more readily understood, reference will now be made to the accompanying drawings, illustrating one embodiment of the same by way of example and wherein:—

Fig. 1 is a perspective view of the device;
Fig. 2 is a plan view thereof in a spread-out condition.

One portion of the device shown, herein-after referred to as the "front" portion to avoid confusion, consists of an upper buoyant compartment 10 and a lower buoyant compartment 11 so connected thereto as to be able to swing upwardly about the lower edge thereof when the device is in use.

These compartments, preferably with square corners as shown, may be made from one or more pieces of material, such as canvas, that may be waterproof if desired, and are preferably filled with kapok or other buoyant material.

Instead of material filling, however, the compartments may be inflated with air.

In the example shown the two compartments are formed from two pieces of material placed together and sewn at the edges 12 and also at a horizontal line 13 so as to form the two compartments 10 and 11, which after filling, are closed by sewing the top and bottom edges 14 of the material employed. The two compartments might be made from a single piece of material folded

over and then sewn to the form shown or they might be made separately and then joined together.

Whatever the method of manufacture employed, the lower compartment 11 is always hingedly connected to the compartment 10.

The rear portion of the device consists of two buoyant compartments 15 and 16 corresponding exactly to the front compartments 10 and 11 respectively and connected thereto by shoulder straps 17. These straps may be separate one from the other or may be constituted by a single piece of material provided with a suitable hole centrally arranged and adapted to pass over the head of the wearer. In either case the material from which the straps are made may be an extension of the material from which the front and/or rear buoyant compartments are made.

When separately applied straps are employed they may merely be connected to the top edges of the containers 10 and 15 or may extend down to the seam 13 and the corresponding seam 18 at the rear. These seams are so positioned and the compartments 10 and 15 so formed that the securing means for the jacket, in the form of a tape or tapes or draw-strings 19, lies or lie either in line 80 with said seams or between said seams and a point not higher than the mid-point of the compartments 10 and 15 while at the same time engaging under the arm-pits of the wearer. By this arrangement there is 90 no tendency for the said compartments to swing upwardly about the securing means nor for the jacket as a whole to ride up on the body of the wearer, who is thus left entirely free from the risk of choking, while 95 as the jacket is held down greater buoyancy is obtained owing to the upper buoyant compartments functioning lower on the wearer. If desired further tapes may be used for this purpose.

The tapes or draw-strings 19, which may be in one or more pieces, are not left loose but are correctly positioned, either by eyelets or loops 20 or, as shown in dotted lines in Fig. 1 and in full lines in Fig. 2, by tubular fabric members 21 secured to the upper compartments. While both these arrangements serve equally well for the purpose of positioning the tapes 19, the use of the tubular members 21 presents the advantages of minimizing the risk of accidental detachment of the tape or tapes and of al-

lowing, in case of emergency, the donning of the jacket without tying of said tapes, in which event the tubular members would prevent displacement of the jacket on the wearer hurriedly entering the water by engaging under his arm-pits.

Although such donning of the jacket without tying is obviously not advisable, it is to be noted that, owing to the restricted 10 upward movement of the jacket, the latter still has a considerable amount of buoyancy.

Moreover, the hinged compartments swing up and so protect the face of the wearer from broken surface water.

15 The preferred form of tying is that indicated in Fig. 2. Each upper compartment has secured to it two guiding loops 21, one of which is shown broken away to indicate the arrangement more clearly, and the loops 20 house pairs of draw-strings 22 and 23, one pair 22 being secured to, say, the compartment 15 and being loose at the front for the purpose of tying, and the second, 23, being secured to the other upper compartment 10. 25 Thus, no matter which way the jacket be put on tying can always be effected in front of the wearer. Moreover, this form of tying allows the jacket to be fitted to any type of human figure.

30 If the buoyant compartments 10 and 11 and/or 15 and 16 are connected together by webs, the tapes may be passed through the webs and tied at the side if desired. Such a web connection could conveniently 35 be formed by providing two seams such as 13 when the compartments are made from two pieces of material as hereinbefore described though such web need not be hollow for the passage of the tape 19 as implied 40 above unless desired. If it is to be made hollow the edges 12 will be left unsewn where it is desired to form the web, i. e. between the two seams 13.

45 Any other suitable connecting means between the buoyant compartments may be employed, while in some cases two or more buoyant compartments may be used side by side in place of single compartments as above described.

50 What I claim is:—

1. A reversible buoyant jacket device comprising two upper buoyant members, a lower buoyant member hingedly connected to each of said upper members, shoulder straps connecting the said upper members, and means for tying said upper members so as to leave the lower buoyant members free to swing about their connections thereto.

60 2. A buoyant jacket device comprising two upper buoyant members, a lower buoyant member hingedly connected to each of said upper members, shoulder straps con-

necting the said upper members, means for tying said upper members to the wearer 65 and means for positioning said tie.

3. A buoyant jacket device comprising two upper buoyant members, a lower buoyant member hingedly connected to each of said upper members, shoulder straps connecting the said upper members and tying means connected to said upper members to engage under the armpits of the wearer to prevent displacement of the jacket.

4. A buoyant jacket device comprising 75 two upper buoyant members, a lower buoyant member hingedly connected to each of said upper members, shoulder straps connecting the said upper members and means for tying said upper members comprising 80 tapes connected to the latter at points not higher than the mid-points of the sides thereof, substantially as set forth.

5. A buoyant jacket device comprising 85 two upper buoyant members, a lower buoyant member hingedly connected to each of said upper members, shoulder straps connecting the said upper members, tapes for tying said upper members to the wearer, and tubular guide members to receive said tapes. 90

6. A buoyant jacket device comprising two upper buoyant members, a lower buoyant member hingedly connected to each of said upper members, shoulder straps connecting the said upper members, tapes for 95 tying said upper members to the wearer and tubular fabric guides connected to said upper members to receive said tapes.

7. A buoyant jacket device comprising 100 two upper buoyant members, a lower buoyant member hingedly connected to each of said upper members, shoulder straps connecting the said upper members, and a pair of tapes connected to each of said upper members for tying the latter to the wearer. 105

8. A buoyant jacket device comprising two upper buoyant members, a lower buoyant member hingedly connected to each of said upper members, shoulder straps connecting the said upper members, a pair of 110 tapes connected to each of said upper members to tie the latter to the wearer, and tubular guides to receive said tapes.

9. A buoyant jacket device comprising 115 two upper buoyant members, a lower buoyant member hingedly connected to each of said upper members, shoulder straps connecting the said upper members, a pair of tapes connected to each of said upper members, and tubular fabric 120 members connected to said upper buoyant members to receive said tapes.

In testimony whereof I have signed my name.

JOHN B. ADAMS.
